MULTI-SPEED TRANSMISSION

Orly Musgrave, Springfield, Ohio, assignor, by mesne assignments, to Mast-Foos Manufacturing Company, Inc., Springfield, Ohio, a corporation of Ohio

Filed Mar. 16, 1964, Ser. No. 79,030

Term of patent 14 years

(Cl. D55—1)

FIG-1

FIGURE 1 is a front perspective view of a multi-speed transmission, showing my new design with the lever broken away in part for convenience of illustration;

FIGURE 2 is a left side elevational view thereof;

FIGURE 3 is a plan view of the design of FIGURES 1 and 2; and

FIGURE 4 is a front elevational view of the design of FIGURES 1-3.

The gear shift lever is fragmentarily shown in FIGURES 2 and 4 and omitted in FIGURE 3 for convenience of illustration.

The dominant features of my design reside in the portions shown in full lines.

I claim:

The ornamental design for a multi-speed transmission, substantially as shown and described.
